[57] CLAIM

The ornamental design for a table attachment for folding chair, as shown and described.

DESCRIPTION

FIG. 1 is a top perspective view of a table attachment for folding chair embodying the my new design;

FIG. 2 is a side elevational view, a chair being shown therein in broken lines for illustrative purposes only.

FIG. 3 is an elevational view thereof showing the side opposite that shown in FIG. 2;

FIG. 4 is a top plan view thereof;

FIG. 5 is a bottom plan view thereof;

FIG. 6 is a front elevational view thereof; and

FIG. 7 is a rear elevational view thereof.
